UNITED STATES PATENT OFFICE.

WALTER E. BARNARD, OF ITHACA, NEW YORK, ASSIGNOR TO BARR-MORSE CORPORATION, OF ITHACA, NEW YORK, A CORPORATION OF NEW YORK.

TYPEWRITER AND THE LIKE.

Application filed August 4, 1926. Serial No. 127,035.

This invention relates to typewriting machines and particularly to means for limiting the travel of the carriage such as for defining the margins, for paragraphing and 5 for tabulating.

The object of the invention is to improve and simplify such limiting means, with which the limits of travel of the carriage may be varied selectively as required or desired in the normal use of the machine, by 10 simple manipulations of conveniently positioned controlling parts, and which will be compact and relatively inexpensive in construction.

15 Various other objects and advantages will be apparent from the following description of an embodiment of the invention, and the novel features will be particularly pointed out hereinafter in connection with the appended claims.

20 In the accompanying drawing:

Fig. 1 is a rear elevation as it appears during the normal typing operation of the tabulating and carriage control mechanism.

25 Fig. 2 is an end elevation of the same.

Fig. 3 is an elevation of a part of the same but with the stop carrying bar or bail in a different operative position; and

30 Fig. 4 is a plan of part of the mechanism for the control of the carriage.

In the illustrated embodiment of the invention, the carriage 1 is mounted for travel transversely of the machine frame or base 2 being guided in its travel by the usual 35 support bar with the interposed ball bearings 3. A margin rack bar 4 is secured at its ends to arms 5 and 6 which depend from and are hinged on studs 7 and 8 of the carriage frame. The arms 5 and 6, with the 40 margin rack bar 4, function as a bail which is capable of swinging movement forwardly and rearwardly of the machine, that is, in a direction transversely or crosswise of the direction of travel of the carriage. The 45 bail is disposed at the rear of the machine, as shown in Fig. 2, and is normally urged forwardly by a coil spring 9 which surrounds one of the studs, such as 8, one end of the spring being interlocked with a portion 50 of the carriage and the other end with the adjacent arm 6 of the bail. The forward movement of the bail under the action of the spring 9 may be limited by the engagement with the frame 2 of tongues 10 on

the arms 5 and 6 which are bent forwardly 55 for engagement with a portion of the carriage 1.

The various carriage control stops are mounted upon the margin rack 4 for adjustment there along to various extents. For 60 example, a margin lock and a bell ringer stop 11, one or more tabulator stops 12 and a margin and paragraph stop 13 may be provided upon the bar 4. Upon the base 2 of the machine a fixed margin stop 14 and 65 a fixed tabulating and paragraph stop 15 may be secured in any suitable manner, but at different distances from the front of the machine. The tabulator and paragraph stop 15 is located further in the rear on the base 70 than the margin stop 14. When the margin bar 4 is in its normal or forward position, as limited by the engagement of the tongues 10 with the carriage frame, the depending or projecting trip portions of the stops 12 75 and 13 will travel with the carriage in the same path or plane and forwardly of the corresponding portions of the tabulator and paragraph stop 15.

The depending portions of the tabulator 80 stops will pass idly above the fixed margin stop 14, but the depending portions of the stop 13 will engage with the fixed margin stop 14 when the carriage is returned to start a line and limit the return of the carriage. The depending portion of the margin lock and bell ringing stop 11 normally passes in the rear of the fixed margin stop 14 and is provided with an outwardly inclined or oblique ear 11^a which engages with the fixed stop 15 by which the ear 11^a and the margin rack will be swung rearwardly to clear the stop 15. The latter is positioned at such a point on the base that the stop 11 will first lock the key mechanism and determine the margin limit before its ear 11^a strikes the fixed stop 15. When the bail is swung rearwardly the depending portions of the margin line lock stop 11, the tabulator stops 12 and the paragraphing and margin stop 13, will travel in paths which intersect with the fixed tabulator and paragraphing stop 15, and will clear the fixed margin stop 14. This rearward position of the bail is shown in Fig. 3, the normal or forward position being shown in Fig. 2.

A shaft 16 is rotatably mounted in brackets 17 on the base 2 so as to extend in a di-

rection parallel to the direction of travel of the carriage. One end of the shaft 16 is bent angularly thereto, as at 18, to form a camming arm just forwardly of but adjacent to the margin rack bar 4. The other end of the shaft 16 is also bent angularly to form a crank arm 19, which terminates in a crank pin 20. The crank pin 20 is received in a looped end 21 of an upstanding 5 arm 22 of a push rod 23. The rod 23 extends forwardly of the machine and adjacent the usual key board is slidably mounted in a comb or plate 24. This rod 23 may also be slidably supported intermediate of its 10 ends if so desired. An arm 25 is secured by its boss 26 and a screw 27 to the forward end portion of the rod 23, and extends upwardly and is provided with a key 28 at its upper end. The arm 25 may also have a 15 forwardly extending pin 29 which is also slidably mounted in the plate or comb 24 in order to prevent rotation of the rod 23, without restriction of its endwise movement. Thus by operation of the key 28 the arm 18 20 of the shaft 16 will be rocked rearwardly to engage and move the margin rack bar 4 or bail rearwardly.

An operating lever 30 may be hinged intermediate of its ends upon one of the studs, 30 such as 7, which mounts the bail. The upper end of the lever 30 may have a finger engaging flange 31 located adjacent to the upper face of the carriage, so as to be accessible for convenient manual manipulation. The lower end of the lever 30 extends along one of the arms of the bail such as arm 5 and carries a tongue 30^a which extends beneath that arm so that when the lever finger piece 31 is shifted forwardly, the bail 35 will be shifted rearwardly. It will be noted, however, that the bail may also be shifted rearwardly by the operation of key 28 without moving the lever 30.

The travel of the carriage in a feeding direction is controlled by an escapement device 33 of any suitable or usual construction, which is connected through a clutch element 34 to a pinion 35 and the latter meshes with a rack 36 carried by the carriage 1. The 40 clutch element 34 is normally urged into a clutched engagement with the pinion by a helical compression spring 37. An arm 38 is mounted for rocking movement upon a shaft or stud 39, and is provided with a lug 40 which engages in an annular groove 41 of the clutch element 34 so that when the arm 38 is rocked in one direction it will shift the clutch element 34 out of clutching engagement with the pinion 35 and thus free 45 the carriage from the control of the escapement device.

A carriage release lever 42 is pivoted at 43 to one of the end plates of the carriage frame, and one of its arms is provided with 50 a radially elongated slot 44 which receives a

pin 45 that projects from an ear 46 of a plate 47. The plate 47 is slidably mounted upon the carriage, and when shifted by reason of the operation of the lever 42 its forward edge will engage with an oblique cam 70 surface 48 of the lever 38, and cause a disengagement of the clutch element 34 from the pinion 35, thus causing a release of the carriage from the escapement device.

The upper ends of the levers 30 and 43 75 are preferably arranged in proximity to one another, so that they may be operated simultaneously if desired by merely pressing them toward the front by one's fingers.

In the operation of a typewriter equipped 80 with such carriage controlling mechanism let it be assumed for example, that the carriage is traveling in a feeding direction under the control of the escapement device that is operated by the type bars which print 85 upon the platen A (see Fig. 2). As the carriage approaches the end of the line, the depending portions of the margin lock stop 11 will engage with and operate the usual or any suitable line lock mechanism (not 90 shown) which locks the type bars against further printing operation. Just prior to this locking of the type bars however, the stop 11 will operate the usual or any suitable bell ringing mechanism (not shown) 95 in order to warn the operator that the carriage is approaching the end of the line. If the operator does not return the carriage, the line lock mechanism becomes effective. The lock mechanism may be released from 100 the control of the stop 11 in order to type a few more characters by a rearward movement of the bail through the operation of the margin release key 28. The details of 105 the margin lock and release margin mechanism do not, per se, form a part of the present invention, but are described and claimed in the copending application of John H. Barr, Ser. No. 79,913 filed Jan. 8, 1926.

After the type bars are released for further operation through the rearward shifting of the bail, the operator may continue to write a limited number of spaces. The operator then returns the carriage to starting position in the usual manner if there is 110 to be no indentation or paragraphing, and this return of the carriage will be limited by the engagement of carriage stop 13 with the fixed margin stop 14. If however, the new line is to be indented or paragraphed the 115 operator in returning the carriage shifts the upper end of the lever 30 forwardly and thus shifts the bail rearwardly while the carriage is being returned. During the return of the carriage under such a condition, the depending portion of stop 13 will move in a path 120 different from that previously traveled and will strike against the fixed stop 15 before it reaches the fixed margin stop 14. The return of the carriage is thus shortened by the 125

distance between the fixed stops 14 and 15, which corresponds to the usual or desired indentations for paragraphs.

If, after the carriage is returned in either manner, one desires to tabulate, the operator shifts the levers 30 and 42 forwardly so as to release the carriage and shift the bail rearwardly. The carriage is then shifted in a feeding direction, free of the control of the escapement, until the first tabulator stop 12 engages with the fixed stop 15 and thus limits the travel of the carriage. The levers 30 and 42 are then released which restores the carriage to the control of the escapement. The tension on the carriage by its propelling spring, however may hold the stop 12 tightly against the fixed stop 15, and the bail may be held against return or forward movement by the friction between the engaging stops. To release the carriage the operator may operate the key 28 to shift the bail further rearwardly and the slight forward movement that the carriage then takes will carry the stop 12 somewhat along a face of the stop 15, so that upon release of the key 28 the carriage will be free to continue in the feeding direction under the control of the escapement device. As soon as the carriage travels a few letter spaces, the stop will clear the fixed stop 15, and the bail will thereupon be moved forwardly into normal position by the spring 9.

If one desires to tabulate at a second point in the same line, the carriage is again released by shifting the levers 30 and 42 forwardly, whereupon the released carriage may be moved in a feeding direction until the next tabulator stop 12 on the bail engages with the fixed stop 15. The following operation is similar to that just described in connection with the first tabulator stop. Any number of tabulating stops 12 may be employed, up to the limit of the length of rack bar 10.

From the foregoing description it will be obvious that one may control the movements of the carriage in both directions for paragraphing and tabulating by simple manipulations of conveniently positioned control devices and simple mechanism.

It will be obvious that various changes in the details, which have been herein described and illustrated in order to explain the nature of the invention may be made by those skilled in the art within the principle and scope of the invention as expressed in the appended claims.

I claim:

1. In a typewriting machine, a carriage, a stop, a support for said stop shiftable with the carriage during travel of the latter in both directions, and also independently shiftable laterally of such travel to place the stop in different planes of travel with said carriage, relatively stationary stops with one

of which the first stop cooperates, depending upon the plane of travel into which it is shifted, a relatively stationary control element disposed along the path of travel of said support and engageable therewith in all positions of the carriage, and key operated means for moving said control element to cause a shift in the path of travel of said first mentioned stop.

2. In a typewriting machine, a carriage, a support member shiftable with the carriage during travel of the latter and also shiftable independently in a direction laterally of such travel so as to move in different paths with such carriage, a base member, a plurality of stops carried partly by each member, with a stop on one member cooperating selectively with those on the other member, depending upon which path said support member is moving in, whereby the extent of travel of said carriage may be selectively varied by shifting said support member laterally into one path or another, and dual means operable separately for shifting said support member laterally while said carriage is in any position of its travel, one of said means being carried by the carriage and the other by said base member.

3. In a typewriting machine, a carriage, a base member relative to which said carriage travels, a bail member hinged by its arms to said carriage for movement with the carriage and also movable independently of the carriage in a direction transverse to the direction of travel of the carriage, a stop carried by the cross strip of said bail member, a stop on said base member with which the bail member stop may cooperate to limit the movement of the carriage when the bail member is adjusted about its hinges into one selected position, a control element on said base member in proximity to and engageable with the cross strip of said bail member in all positions of said carriage and movable to shift said bail member laterally to change the path of travel of the stop carried by said bail members.

4. In a typewriting machine, a carriage, a base member relative to which said carriage travels, a bail member hinged by its arms to said carriage for movement with the carriage and also movable independently of the carriage in a direction transverse to the direction of travel of the carriage, a stop carried by the cross strip of said bail member and a plurality of stops carried by the base member at different distances laterally from the carriage, and with which the carriage stop may cooperate selectively to limit travel of the carriage depending upon what position the bail member is placed by movement about its hinges.

5. In a typewriting machine, a carriage, a base member relative to which said carriage travels, a bail member hinged by its arms to

- said carriage for movement with the carriage and also movable independently of the carriage in a direction transverse to the direction of travel of the carriage, a plurality 5 of tabulator stops carried by the cross strip of said bail member, a stop on said base member with which the tabulator stops may cooperate to limit the movement of the carriage when the bail member is adjusted 10 about its hinges into one selected position, said tabulator stops being adjustable in the direction of travel of the carriage whereby the point in the path of travel of the carriage where the carriage will be stopped may 15 be varied, and means on said base member operable on said bail member in all positions of the carriage for further driving said bail member to disengage said stops if they should not disengage automatically upon 20 completion of the tabulating movement.
6. In a typewriting machine, a carriage, a base member relative to which said carriage travels, a bail member hinged by its arms to said carriage for movement with the 25 carriage and also movable independently of the carriage in a direction transverse to the direction of travel of the carriage, a stop carried by the cross strip of said bail member, and a plurality of stops carried by the 30 base member at different distances laterally from the carriage, and with which the carriage stop may cooperate selectively to limit travel of the carriage depending upon what position the bail member is placed by movement about its hinges, a stop on one of said members being adjustable in the direction of travel of the carriage whereby the point in the path of travel of the carriage where the carriage will be stopped may be varied. 35
- 40 7. In a typewriting machine, carriage member, a base relatively to which the carriage travels to letter space, an escapement controlling the travel of the carriage, means including a lever carried by the carriage for releasing the carriage from the control of 45 said escapement, a controlling member carried by said carriage and shiftable laterally thereof, a stop mounted on said controlling member and shiftable by the lateral movement of said controlling member into positions in which it moves in different paths with said carriage, and a stop on said base 50 with which said first stop cooperates to limit the travel of the carriage when shifted laterally with said controlling member into one selected position, said controlling member having an operating handle part adjacent said lever and convenient for operation concomitantly with said lever, the movement of 55 said handle part and said lever toward one another causing a release of the carriage and a setting of said member to limit the movement of the carriage. 60
8. In a typewriting machine, a carriage

- member, a base relatively to which the carriage travels to letter space, an escapement controlling the travel of the carriage, means including a lever carried by the carriage for releasing the carriage from the control of said escapement, a controlling member carried by said carriage and shiftable laterally thereof, a stop mounted on said controlling member and shiftable by the lateral movement of said controlling member into positions in which it moves in different paths with said carriage, and a plurality of stops on said base at different distances laterally from the carriage and with one or the other of which said first stop cooperates to limit the travel of the carriage when shifted laterally with said controlling member into either of the two selected positions, and said controlling member having an operating handle part adjacent to said lever and convenient for operation concomitantly with said lever, whereby said carriage may be released for movement and the controlling member set to limit its movement. 65
9. In a typewriting machine, a carriage, a stop supporting element shiftable with said carriage during travel of the latter in both directions and also independently shiftable in a direction laterally of the carriage travel, stops carried by said element so as to move in different paths with said carriage depending upon the extent of the lateral adjustment of said element, a base element relative to which the carriage moves, stops carried by said base element, with which the stops on the supporting element engage selectively, depending upon the lateral adjustment of said supporting element, to control the travel of the carriage, means movable with the carriage for laterally shifting said supporting element selectively into different positions to render selected stops effective in controlling the travel of the carriage, and key operated means on said base element for also laterally shifting said supporting element laterally, independently of the position of the carriage. 90
10. In a typewriting machine, a carriage, a stop supporting element shiftable with said carriage during travel of the latter in both directions, and also independently shiftable in a direction laterally of the carriage travel, stops carried by said element so as to move in different paths with said carriage depending upon the extent of the lateral adjustment of said element, a base element relative to which the carriage moves, stops carried by said base element, with which the stops on the supporting element engage selectively, depending upon the lateral adjustment of said supporting element to control the travel of the carriage, and means movable with the carriage for laterally shifting said supporting element selectively into different positions to render selected stops effective in controlling the travel of the carriage, and key operated means on said base element for also laterally shifting said supporting element laterally, independently of the position of the carriage. 95
- 115
- 120
- 125

tively into different positions to render selected stops effective in controlling the travel of the carriage, the stops upon one of said elements being adjustable in the direction of travel of the carriage so as to vary the points at which their control of the carriage is effective.

11. In a typewriting machine, a base, a carriage, a bail hinged by its arms to said carriage so as to travel therewith and also be free to swing laterally thereof, means for holding the bail yieldingly in one lateral position, a lever moving with the carriage and engageable with the bail, to shift it laterally into different positions, cooperating stops carried by said bail and base for limiting the travel of the carriage beyond limits depending upon the position into which the bail is shifted laterally, and key operated means for also shifting the bail laterally at any position it may assume in its travel with the carriage.

12. In a typewriting machine, a base, a carriage, a stop supporting member movable with the carriage and shiftable independently thereof laterally of the travel of the carriage, a paragraph stop, a margin stop, and a tabulating stop carried by the supporting member, and additional stops on said base in positions in which the margin stop engages with said additional stops selectively, depending upon the lateral position into which the supporting member has been adjusted, and said tabulator stop engages with one of said additional stops when the sup-

porting member has been shifted laterally into one position.

13. In a typewriting machine, a base, a carriage, a bail hinged by its arms to said carriage so as to travel therewith and also be free to swing laterally thereof, stop elements carried by said bail and having portions running in different paths forwardly and rearwardly of the carriage as they move with the carriage in its travel, and a plurality of fixed stops on said base disposed at different points considered forwardly and rearwardly of the base with which the stop elements cooperate selectively depending upon the position into which the bail is swung.

14. In a typewriting machine, a base, a carriage, a stop supporting member movable with the carriage and shiftable independently thereof laterally of the travel of the carriage, a paragraph stop, a margin stop, and a tabulating stop carried by the supporting member, and additional stops on said base in positions in which the margin stop engages with said additional stops selectively, depending upon the lateral position into which the supporting member has been adjusted, and said tabulator stop engages with one of said additional stops when the supporting member has been shifted laterally into one position, part of said stops being adjustable in the direction of travel of the carriage to vary the limits of travel of the carriage.

WALTER E. BARNARD.
